UNITED STATES PATENT OFFICE.

EARL H. SHERBONDY, OF CLEVELAND, OHIO, ASSIGNOR OF ONE-HALF TO ROBERT R. ABBOTT, OF CLEVELAND, OHIO.

GASOLENE SYSTEM FOR ENGINES.

1,323,415.

Specification of Letters Patent.

Patented Dec. 2, 1919.

Application filed April 23, 1917. Serial No. 163,772.

To all whom it may concern:

Be it known that I, EARL H. SHERBONDY, a citizen of the United States, and a resident of Cleveland, county of Cuyahoga, and 5 State of Ohio, have invented a new and useful Improvement in Gasolene Systems for Engines, of which the following is a specification, the principle of the invention being herein explained and the best mode in which 10 I have contemplated applying that principle, so as to distinguish it from other inventions.

The present invention, relating as indicated to a fuel supply system for engines, 15 is more particularly concerned with a system of the type commonly known as a vacuum system, and is intended to avoid the difficulties which have been met with the systems of this type which are now in use. 20 A further object of the invention is the simplification of such a system involving the use of fewer parts than the systems now in use, and avoiding the complicated mechanisms which are liable to get out of order 25 and which do not at all times operate successfully. To the accomplishment of the foregoing and related ends, said invention, then, consists of the means hereinafter fully described and particularly pointed out in 30 the claim.

The annexed drawing and the following description set forth in detail certain mechanism embodying the invention, such disclosed means constituting, however, but one 35 of various mechanical forms in which the principle of the invention may be used.

In said annexed drawing:—

Figure 1 is a side elevation partially in 40 section, and showing more or less diagrammatically the parts and connections of my improved system; and Fig. 2 is a longitudinal section through a modification of one part of the apparatus.

Referring now to Fig. 1, there is shown 45 a reservoir or tank 1 adapted to be filled with liquid fuel and connected by means of a conduit 2 with a constant level chamber 3. This chamber 3 is closed to the atmosphere and is provided with an internal partition 4 50 rising to a predetermined height therein and separating the chamber into two chambers 5 and 6. The part 6 is of course in the form of an open receptacle and the conduit 2 enters the same below the top of the partition 55 4. From the bottom of the chamber 5 there

is a return conduit 7 leading to the reservoir 1 and serving to return to the reservoir any fuel which overflows the partition 4. The partition thus serves to fix the maximum depth of fuel which can be maintained 60 in the chamber 6. Extending from the chamber 3 out of the portion 6 thereof and at any convenient height is a fuel supply nozzle 8, which enters and is disposed within a suitable mixing chamber 9 of the carbureter. 65

As already explained the partition 4 determines the maximum fuel depth in the chamber 6 and means are also provided for maintaining this maximum depth therein, 70 thus rendering the chamber 6 capable of operating as does the float chamber of the ordinary carbureter and supplying fuel to the nozzle 8 connected thereto under a constant head. This means just referred to 75 may take any of several forms, and I have shown in Figs. 1 and 2 two constructions adapted to maintain a constant supply of fuel in the chamber 6 by lifting the same from the tank 1 through the conduit 2. 80 Thus in Fig. 1 there is shown an intermediate chamber 10 into the bottom of which the conduit 2 extends, where there is mounted a check valve 11 adapted to permit the flow upwardly through the conduit 2, 85 but not in the reverse direction. Extending into this chamber 10 is a tube 12 forming a part of the conduit 2 and the tube 12 is extended to within a short distance of the bottom of the chamber 10. A second ball 90 valve 13 is mounted in the tube 12 at about the level of the top of the chamber 10, this valve also serving to permit the flow of fuel in the direction of the tank 3 only and not in the reverse direction. Connected to the 95 top of the chamber 10 is a conduit 14 extending to any suitable pulsating means, such as a pump 15, or, as shown in Fig. 2, a diaphragm 16, the diaphragm being operated by the pulsations in the engine cylinder, to 100 which it is connected on one side by means of a conduit 17.

The function of this pulsating means is to produce intermittent variations in the pressure existing in the chamber 10 on the 105 liquid therein. When this pressure is lowered, as it is on every outward stroke of the piston 18 in the pump, fuel is drawn through the conduit 2 into the chamber 10, but is not forced into the tube 12 on this 110

stroke of the pump. Upon every increase in the pressure existing in the chamber 10, (caused by the inward stroke of the piston 18) the fuel in the chamber 10 is forced upwardly through the tube 12 and conduit 2 and into the chamber 3.

It is a matter of indifference as to whether the chamber 3 is filled at a higher rate of speed than necessary as the excess fuel 10 drawn into the chamber merely overflows into the chamber 5 and is returned through the line 7 to the reservoir 1. A constant supply of fuel is thus maintained in the chamber 6 and this fuel is therefore supplied 15 to the nozzle 8 under a constant head, while a very small pump will produce sufficient quantity of fuel to maintain the chamber 6 in a filled condition, and, if desired, the pump can be replaced by mechanism 20 such as is shown in Fig. 2, which is operated directly from the engine cylinder. The present system is not only extremely simple in its construction, but it avoids the use of any float in the chamber 6, which replaces the 25 float chamber of the carburetor and thus

combines the advantages of a vacuum system with the usual carburetor without the defects of the latter.

I therefore particularly point out and distinctly claim as my invention:—

In a device of the character described, the combination of a liquid fuel reservoir, a fuel feed chamber, a return connection from said chamber to said reservoir disposed at a pre-determined level in said chamber, conduits 30 leading from said reservoir and chamber and terminating one above the other, check valves disposed in said conduits permitting flow away from said reservoir and toward said chamber only, an intermediate chamber of appreciable size disposed about the ends of said conduits, and means adapted to alternately increase and decrease the pressure in said intermediate chamber, thereby alternately drawing fuel thereinto and then 40 forcing it into said conduit leading to said fuel reservoir.

Signed by me, this 20 day of April, 1917.

EARL H. SHERBONDY.
